DISCHARGE VALVE

Frank B. Allen, Verona, N. J., assignor to
C-O-Two Fire Equipment Company, Newark,
N. J., a corporation of Delaware

Application May 4, 1945, Serial No. 592,008

2 Claims. (Cl. 137—466)

1

This invention relates to discharge valves for fire extinguishing apparatus.

Fire extinguishing systems of the class contemplated in this invention comprise one or more cylinders of carbon-dioxide under great pressure which is discharged through a suitable valve and a piping system to the point desired.

Because of the great pressure under which carbon-dioxide is stored in these cylinders it has been usual to provide a disc which can be perforated to effect release of the gas. When such devices are used on ships of war which are subject to shocks and impacts because of the firing of their own weapons and enemy attack, it is important that the release valve does not operate when subject to such shocks. At the same time any device intended to prevent such premature discharge of the gas must not complicate the operation of a device unduly. It will be appreciated that a disc which is to be perforated by a moving plunger can be perforated by a number of blows from the plunger engendered by a series of shocks or impacts, any one of which is insufficient to completely perforate the disc alone.

It is, therefore, an object of the present invention to provide a release valve for carbon-dioxide fire extinguishing systems which is not subject to premature discharge because of shocks.

It is a further object of the present invention to provide a discharge valve which requires no replacement of parts upon refilling of the cylinder after discharge.

Another source of premature discharge of this kind is the building up of pressure over the operating piston due to leaks, when a series of cylinders and discharge heads are connected as described in the United States patent to S. E. Allen, No. 2,271,851. In that patent, a vent valve is provided for preventing the pressure from building up sufficiently to operate the mechanism.

It is an object of this invention to provide a release valve for fire extinguishing systems which is inherently incapable of release by leaks in the system.

In addition to the above considerations in connection with the operation of fire extinguishing equipment involving a disc to be pierced, the pressure operated type of mechanism has another limitation. It can be appreciated that the force required to pierce a disc in the type of extinguisher under consideration is independent of the temperature and of the pressure within the container. It is necessary to make the disc heavy

2

enough to prevent rupture even at the highest temperature likely to be encountered. Accordingly, when the temperature is very low, the pressure within the cylinders drops, and this low pressure is called upon to operate the disc piercing member to perforate a disc which is designed to withstand a high pressure engendered by possible high temperature to which the equipment may be subjected.

10 It can be conceived, then, that the ideal situation would be one in which the resistance to opening of the valve was proportional to the pressure available to so open the valve.

Accordingly, it is a further object of the present invention to provide a release mechanism for fluid stored under pressure in which the pressure required to operate the mechanism is proportional to the pressure available.

Referring now to the drawings, 15 Fig. 1 is a section taken on a plane through the axis of a valve comprising one embodiment of my invention;

20 Fig. 2 is a section taken along line 2—2 of Fig. 1; and

25 Fig. 3 is a section taken along line 3—3 of Fig. 1.

The device shown consists of two main parts; a lower section or cylinder valve 10 and an upper section or discharge head 11, which are connected by means of the union nut 12. The cylinder valve has a threaded portion 13 which is screwed into the neck of a container for compressed gas. An internally threaded portion 14 supports a syphon tube which extends down into the cylinder and assures that substantially all of the liquid within the cylinder is discharged. This cylinder valve body carries a safety device in the form of a disc 15 which would be ruptured under excessive pressure. This disc is held in place over a washer 16 by means of a plug 17 threaded into the valve body 10. It will be noted that this plug has an opening extending partially through it which is intercepted by opposed openings 18. The opposition of openings 18 is to prevent the generation of unbalanced forces in the event that disc 15 ruptures and the gas discharges through the ports. A filling opening may be provided in the cylinder valve. In the shown form this is a short neck 19 provided with external threads for coupling to a source of carbon-dioxide. A bore extends through this neck to the central passage 20 of the valve. A ball 21 serves as a check to prevent discharge of the fluid from the cylinder upon uncoupling of

the supply hose. The plug 22 and cap 23 serve to further retain the carbon-dioxide.

In order to provide a valve which can be opened to release the contents of the cylinder, the upper end of the valve body carries a valve seat 24 forming part of the bushing or partition member 25 which is threaded into the valve body 10. A valve assembly 26 cooperates with the valve seat 24 to form a gas-tight joint when the valve is in the position shown in Fig. 1. This assembly consists essentially of a valve body 27 which is non-circular as shown in Fig. 3 to permit flow past the valve when it is open. The body 27 carries a gasket 28 which bears against the valve seat and is secured to the body by means of a screw 29. A spring 30 serves to retain the valve in the position shown in Fig. 1 except when it is forced downwardly by a mechanism to be described.

The discharge head 11 consists of a body member 31 which can be secured to the cylinder valve by means of the coupling nut 12 as before described. A stem 32 provided with an axial bore 33 passes through the center opening of the bushing or partition member 25 and upon downward movement will depress the valve 26. In order to prevent leakage of the gas around the stem 32 a packing 34 is provided. To permit entrance of the gas to the center bore 33 a plurality of openings 35 are made in the stem 32.

The upper end of the stem 32 is secured to a piston 36 which is movable within the discharge head 31. This piston is of greater area than the area of the valve 26. A washer 37 on the lower face on the piston cooperates with the upper sealing surface of the bushing 25 to form a gas-tight seal when the piston is in its lowermost position. The packing 38 serves to prevent discharge of the gas through the space between the piston and the bore in which it operates.

The air or gas displaced by the piston on its downward movement passes around the bushing 25, which is made hexagonal (as shown in Fig. 2) to provide a clearance, through openings 39 in the valve body and out through openings 40 in the coupling 12.

It will be noted that both packages 34 and 38 are in the form of rings of rectangular cross-section with V-shaped grooves in the side presented to the higher pressure. A slight clearance is provided in the recess holding each packing. This type of packing has the property of being extremely efficient under high pressure, but permits leakage of gas at low pressures. Thus, failure of check valves in the line as described in the above mentioned patent will permit the gas to leak past packing 38 and out through openings 39 and 40, and any slow leaks developing past the valve assembly 26 will cause gas to pass the packing 34, and thence pass outward through the opening 39 and 40.

In order to initiate downward movement of the piston 35 and the stem 32, an operating rod 41 is secured to or made part of the piston. This rod has been shown as being hollow for substantially all of its length for the purpose of reducing its mass as much as possible. Packing means 42 prevents escape of the gas through the annular space between the operating rod and the body of the discharge head. A spring 43 normally holds this rod in the position shown. A ball check 44 prevents the passage of gas in any direction except upwardly. A discharge outlet 45 for the released gas is connected to the discharge line.

The operation of the device is as follows:

Upon forcing the operating rod 41 downwardly, which may be done by hand or by means of some automatic device, the stem 32 forces the valve 26 away from the valve seat 24, thus permitting gas to pass upwardly through the valve stem 33 past the ball check 44 and into the space above the position. Because the area of the piston 36 is greater than the area of the valve 26, an unbalance is produced which forces the piston 36 downwardly until it is stopped by the contact of the washer 37 and the top of the bushing 25. Gas continues to flow out of the container until substantially all of it is released. When the pressure above the piston 36 decreases sufficiently due to this discharge, the springs 43 and 30 return the parts to the position shown in Fig. 1.

It will be noted that in the event of a shock or impact being imparted to the entire valve assembly as, for instance, during the firing of heavy guns on a vessel in which the device is installed, the operating rod 41 may be forced downwardly to some extent. However, it is comparatively simple to so relate the strength of the spring 43 and the mass of the operating rod 41 and associated parts so that even if the stem 32 comes in contact with the valve assembly 26 the force is insufficient to unseat the valve. The spring 43 need not be so powerful as would be necessary if it were absolutely essential that the stem 32 be prevented from touching the valve. In the case of a disc which is intended to be perforated by the equivalent of stem 32 it would be necessary to so prevent the bottom of the stem from touching the disc at any time under such impacts, because continued blows of the stem on the disc under such impacts would eventually rupture the disc and cause discharge. Thus, the device does not become too difficult to operate, and furthermore, the difference in pressure between the inside of the cylinder and the outlet 45 need not be so great in order that the valve may remain open. This means that there is a more complete discharge from the cylinder.

The device may also be operated by the pressure of gas on the upper side of the piston 36 alone, as, for example, when another cylinder of carbon-dioxide is connected to a header. In such a case, release of gas from any one of the cylinders will operate the valves on the others by forcing their respective pistons downwardly. In that event, the use of a valve, rather than a perforatable disc, becomes particularly advantageous. The pressure above the piston 36 bears a constant ratio to the pressure below the valve 26, depending on the design of the system. Accordingly, there is the same certainty of operation at low temperatures as at high, decrease of pressure available to force the piston down being accompanied by a corresponding decrease in the pressure resisting such downward movement.

The above description is of a preferred embodiment of my invention but is to be understood that I do not wish to be limited to the particular description illustrated and that the scope of this invention is best construed by means of the following claims.

I claim:

1. A discharge valve for fluid under high pressure comprising a housing in separable upper and lower sections, a union nut to secure the sections together, the upper section having a discharge outlet, and a piston chamber, a piston in the piston chamber, a hollow piston stem apertured at the upper end thereof, a ball check 70 to close the passage through the piston stem

against downward fluid flow, the lower section having a threaded lower end to be secured in the outlet of a high pressure fluid container, the lower section having a passage therethrough with an enlarged portion at its upper end defining a valve chamber, an apertured partition member threadedly engaged in the upper end of the enlarged passage to form the upper wall of the valve chamber, a valve seat formed on the lower side of the partition about the aperture, the upper end of the aperture in the partition member enlarged to form a packing recess, a packing in the recess, a packing nut threadedly engaged in the upper end of the packing recess, a valve member in the valve chamber adapted to engage the valve seat, resilient means normally urging the valve member against the valve seat, the effective area of the piston greater than the area enclosed by the valve seat, the lower end of the piston stem apertured to provide a fluid passage therein, the valve stem normally spaced from the valve member, and resilient means normally urging the valve stem away from the valve member.

2. A discharge valve for fluid under high pressure comprising a housing in separable upper and lower sections, a union nut to secure the sections together, the upper section having a discharge outlet and a piston chamber, a piston in the piston chamber, a hollow piston stem apertured at the upper end thereof, a ball check to close the passage through the piston stem against downward fluid flow, the lower section having a threaded lower end to be secured in the outlet of a high pressure fluid container, the lower section having a passage therethrough with an enlarged portion at its upper end defining a valve chamber, the intersection of the wall of the passage and of the enlarged portion thereof forming a shoulder, an apertured partition member threadedly engaged in the upper end of the enlarged portion to form the upper wall of the valve chamber and the lower end of the cylinder, a valve seat formed on the lower side of the partition about the aperture, means

5
